UNITED STATES PATENT OFFICE.

ROBERT SMITH, OF QUEBEC, QUEBEC, CANADA.

DESIGN FOR A LINK-LIFTER.

SPECIFICATION forming part of Design No. 15,608, dated December 9, 1884.

Application filed September 24, 1884. Term of patent 14 years.

To all whom it may concern:

Be it known that I, ROBERT SMITH, of Quebec, Province of Quebec, Canada, have invented and produced a new and original Design for a Link-Lifter for Railroad-Car Couplings, of which the following is a specification.

This invention relates to link lifters or bails; and it consists in a novel configuration of the same, as shown in the drawing and herein-
10 after described and claimed.

Reference is to be had to the accompanying drawing, forming a part of this specification, which is a view in perspective of a link-lifter for car-couplings having my new design.

15 A indicates the cross-bar of the bail or lifter, of flat configuration on its face, and straight or nearly straight in direction of its length, and B B the arms thereof, also of flat configuration on their faces, but curved and
20 straight in direction of their length, the same presenting a straight-edge contour for a given distance at their inner ends, a a, and a grace-

ful curved-edge contour for their continuous portions b b, bowing outward away from one another and vanishing at their outer ends, c c, 25 into line with the bar A, as shown.

Having thus described my design, I claim as new and desire to secure by Letters Patent—

The within-described design for a link-lifter for car-couplings, which consists of the cross-bar A, of flat configuration on its face, and straight or nearly straight in direction of its length, and the arms B B, also of flat configuration on their faces, with their main portions b b made to present reverse-curved contours terminating at their inner ends, a a, in straight lines or courses, and vanishing at their outer ends, c c, into line with the cross-bar, as shown. 30 35
